UNITED STATES PATENT OFFICE

ORLO A. BARTHOLOMEW, OF KANSAS CITY, MISSOURI

PROCESS AND APPARATUS FOR BARKING LOGS

Application filed March 14, 1929. Serial No. 346,943.

This invention relates to a machine for removing the bark from logs and is more particularly designed, although not limited to this use, for removing the bark from relatively long logs for use as telephone, telegraph, and electric poles, piles etc.

The principal object of this invention is to provide a simple, easily operated, device which will handle a relatively large quantity of logs simultaneously and will remove the bark therefrom without damage to the log itself.

Another object is to so construct the machine that the logs can be quickly and easily placed therein and removed therefrom without the use of auxiliary hoists or loading devices.

A further object of the invention is to utilize the well known fact that logs abrading against themselves will effectively remove the bark from each other, especially when immersed or water soaked.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 illustrates a cross section through the invention in the charging position.

Fig. 2 is a similar cross section illustrating the device in operation.

Fig. 3 is a similar cross section illustrating the device in the discharging position.

Fig. 4 is a fragmentary plan view of the device when in the position of Fig. 2.

Fig. 5 illustrates a cross section through an alternate form of the invention.

The invention comprises a barking tank 10, preferably formed with a semi-cylindrical bottom. To one side of the barking tank 10 is a receiving pond or tank 11, which is separated from the tank 10 by means of a low partition 12. Extending axially throughout

the tank 10 is a horizontal shaft 13 carried in suitable bearing boxes 27. Cross members 14 are secured to shaft castings 15 which are keyed or otherwise secured to the shaft 13, at spaced intervals.

The cross members 14 may be connected by means of planks or other members 16 extending longitudinally of the tank 10. If the device is used, however, for uniform lengths of logs the planks 16 may be omitted, as the cross members 14 will effectively act against the logs.

Supported above each of the members 14 is an arcuate truss member 17 which is secured to the extremities of the member 14 and supported by means of radial spokes 18 from the shaft casting 15. At one extremity of each of the members 14 the truss member 17 projects beyond the face thereof as shown at 19.

The logs are fed to the barking tank 10 from any suitable receiving deck 20, upon which they are held by latches 21 operated from any suitable operating mechanism through the medium of a connecting rod 22. The tanks 10 and 11 are filled with water substantially to the level of the shaft 13.

While the device is being charged or filled with logs the operating members occupy the position illustrated in Fig. 1 and the latches 21 are released to allow the logs to roll from the deck 20 into the tank 10. When a sufficient number of logs have been placed in the tank 10, the latches 21 are raised to support the logs upon the deck 20 and the shaft 13 is rotated to the solid line position of Fig. 2. This allows all of the contained logs to float or roll to the highest point, as illustrated. The shaft is then reversed to the position indicated in broken line in Fig. 2, allowing the logs to roll or float back to the other side of the tank 10. The shaft 13 is now reciprocated between the two positions indicated in Fig. 2, until the action of the logs rolling and pounding against each other, against the sides of the tank 11, and against the planks 16, has removed the bark therefrom.

It will be noted that during the bark removing process the projecting extremities 19 on the truss member 17 prevent the logs from floating into the receiving tank 11.

When the bark has been sufficiently removed the shaft 13 is rotated to the position of Fig. 3 and, as the members 14 and the planks 16 rise on the discharging side, the logs will float and roll into the receiving tank 11. The shaft is now rotated in the direction of the arrow of Fig. 3, to the position of Fig. 1, when a new charge of logs is received.

It will be noted the arcuate truss members 17 act to hold the logs in the receiving tank 10 while the barking device is passing to the charging position.

The logs can be removed from the receiving tank 11 in any desired manner, such as by an elevator chain or they can be simply floated from the tank to the desired point. In fact the receiving tank 11 could be the storage pond of the plant if such an arrangement was convenient.

The shaft 13 can be rotated in any desired manner, such as by an electric motor through the medium of suitable gears, the motor being preferably of the direct current, quick starting and easily reversing type. The shaft 20 could also be rotated through the medium of gears and clutches from a gas or gasoline engine. In fact the method of rotating the tank is within the skill of any mechanic. One method, however, for rotating the shaft is 25 illustrated in Fig. 4, in which two steam cylinders 23 supporting cross head guides 24, actuate connecting rods 25.

The connecting rods 25 are secured to crank disks 26 secured on the extremities of 30 the shaft 13. These cylinders are under the control of an operator who can, by manipulation of his throttle valve, reciprocate or rotate the shaft 13 as desired. Steam is probably the better method for actuating the device in that the exhaust steam from the cylinders 23 can then be employed for heating the 35 water in the tank 10 so as to quicken the bark softening action thereof. The bark removed from the logs and other refuse about the plant will provide sufficient fuel to provide 40 the steam.

The removed bark will be forced into the receiving tank 11 by the action of the discharging wave or surge and can then be removed 45 from the water through screens or in any other desired manner.

In Fig. 5 I have illustrated an alternate form of the invention employing the same principle as the preceding form. In this 50 form the logs are discharged from the deck 20 by means of latches 21 as in the preceding form. This form also employs a tank, such as illustrated at 28 throughout the length of which an operating shaft 29 extends. The 55 shaft 29 is arranged to be reciprocated, between the broken line and solid line positions of Fig. 5, by means of cranks 30 and connecting rods 31, or in any other desired manner.

The shaft 29 carries cross members 32 55 which may be provided with projections on

their lower faces, such as indicated at 33, to facilitate the bark removal. The cross members 32 in this form are not connected together by longitudinal members or planks but are spaced apart so that the arms of the discharge spiders 34 can pass therebetween. 70 The spiders 34 are carried in spaced apart relation upon a discharge shaft 35 which extends throughout the length of the tank.

At the feed side of the tank 28, arcuate side members 36 are hinged at 37 and operated by means of a connecting rod 38 from any suitable mechanism.

The alternate form operates as follows: The side members 36 are drawn outwardly 80 to the broken line position and the latches 21 are released. This allows the logs to fall between the side members 36 and the extremities of the cross members 32. After a sufficient number of logs are in place the side members 36 are forced forwardly so as to force the logs beneath the members 32. The shaft 29 is now reciprocated backwardly and forwardly until the bark is worn away by the abrasion of the logs. 90

To discharge the logs, the shaft is stopped in the broken line position of Fig. 2 and the discharge shaft 35 is rotated so that the arms of the spiders 34 will pass upwardly and force the logs from the barking portion of the device into a receiving portion, indicated at 39. Thus the arms of the spiders 34 serve for the left side of the barking tank and the side members 36 serve as the right side of the barking tank. 95

The logs can be removed from the portion 100 39 either by floating them away or by any of the usual log elevating and conveying devices.

While the invention has been described as 105 particularly applicable for long poles, it is desired to be understood that it is not limited to this use, but will be found valuable for removing the bark from logs of any length. At the present time bark is usually removed 110 from short bolts for pulp purposes by rolling them in a drum, the ends of the bolts become mashed or broomed and the dirt and rocks with which they are rolled are pounded into the broomed ends. This dirt is carried 115 to the grinding machines, causing rapid wear, damage, and impure pulp. With the use of the present invention, however, the dirt and rocks settle immediately to the bottom of the tank and are not pounded into 120 the wood. Rossing machines, while very satisfactory for removing bark, are expensive to operate, require constant resharpening of the knives and remove a large percentage of the valuable pulp wood in addition to the bark. These disadvantages will be obviated 125 by the use of the present invention upon pulp wood.

While a specific form of the improvement has been described and illustrated herein, 130

it is desired to be understood that the same may be varied within the scope of the appended claims, without departing from the spirit of the invention.

5 Having thus described the invention, what I claim and desire to secure by Letters Patent is:—

1. A device for removing the bark from logs comprising: a tank adapted to contain 10 water; a shaft extending longitudinally of said tank; cross members carried by said shaft; and means for oscillating said shaft so that said cross members will force said logs alternately below the surface in said tank at 15 opposite sides thereof.

2. Log barking apparatus comprising: a tank adapted to contain water and oscillating members extending across in said tank; and means for alternately forcing the opposite extremities of said members below the surface of said water so as to force logs below the surface and allow them to float back to said surface at the sides of said tank.

3. Log barking apparatus comprising: a 25 tank containing water; a barking member in said tank adjacent the surface of said water and a pivotal support for said barking member and means for rocking said member so that said member will act to alternately force logs beneath the surface at one side of said tank and allow them to float to the surface at the opposite side thereof.

4. A device for removing the bark from logs comprising: a tank adapted to contain 35 water; a shaft extending longitudinally of said tank; cross members carried by said shaft; and means for oscillating said shaft so that the extremities of said cross members will alternately enter said water, so as to force the logs therebelow and allow them to 40 float toward the elevated extremity.

5. A device for removing the bark from logs comprising: a barking tank adapted to contain water; a shaft extending longitudinally of said tank adjacent the surface of said water; cross members carried by said shaft; means for oscillating said shaft so that the extremities of said cross members will alternately enter said water; a receiving tank adjacent said barking tank and open thereto; means for rotating said shaft so that said cross members will force the logs from said barking tank into said receiving tank; and an arcuate truss member carried by the upper sides of said cross members and acting to prevent the return of the logs from the receiving tank to the barking tank.

6. A device for removing the bark from logs comprising: a barking tank adapted to contain water; a shaft extending longitudinally of said tank adjacent the surface of said water; cross members carried by said shaft; means for oscillating said shaft so that the extremities of said cross members will alternately enter said water; a receiving tank ad-

jacent said barking tank and open thereto; and means for rotating said shaft so that said cross members will force the logs from said barking tank into said receiving tank; and a downwardly projecting member at one extremity of said cross members arranged to prevent the passage of logs from said barking tank to said receiving tank during the barking operation.

7. A device for removing the bark from logs comprising: a tank adapted to be filled with water; a horizontal shaft arranged substantially at the surface of said water; cross members carried by said shaft; means for oscillating said shaft so that the extremities of said cross members will alternately force said logs into said water; and means for placing said logs under said cross members, said means comprising hinged side members arranged to swing away from and toward the extremities of said cross members.

In testimony whereof, I affix my signature.
